To all whom it may concern:

Be it known, that I, Samuel H. Sailor, of the District of Kensington, in the county of Philadelphia, & state of Pennsylvania, have invented or produced a new design for stoves, and I do hereby declare that the following is a full & exact description of the same.

The design consists in the application of certain ornaments, which are represented in the accompanying drawings, to cast iron plates which are intended for coal stoves.

In the drawings the several parts of the stove are represented as follows, viz:

Fig 2. The bottom plate.

Fig 3. The plate on which the cylinder rests.

Fig. 4. The plate above the cylinder

Fig. 5. The ring, which is designed as a cap to a sheet iron body, to be placed above the cast iron cylinder. The cover, which is represented at f in fig. 5, forms no part of my design.

Fig 6. A side plate of the base.

Fig 7. The foot.

a. The front of the ash drawer.

b. The screen, which surrounds the cast iron cylinder.

No 409

- c. The plate represented more fully in fig. 3..
- d. The Hearth.
- e. The plate represented more fully in Fig 4.

What I claim as my invention and desire to secure by Letters Patent, is the ornamental design for a stone, as herein described, and as represented in the annexed drawings.
